United States Patent

Des. 241,135
Patented Aug. 24, 1976

241,135

SPECTACLE FRONT

Jack Bloch, Leominster, Mass., assignor to Foster
Grant Co., Inc., Leominster, Mass.

Filed Nov. 27, 1974, Ser. No. 527,932

Term of patent 14 years

Int. Cl. D16—06

U.S. Cl. D16—78

FIG. 1

FIG. 2

FIG. 3

FIG. 1 is a front elevational view of a spectacle front showing my new design.

FIG. 2 is a top plan view thereof.

FIG. 3 is a side elevational view thereof.

The rear of the spectacle front not shown, conforms in configuration to the front shown.

The side not shown has substantially the same appearance as the side shown.

I claim:

The ornamental design for a spectacle front, substantially as shown and described.
